UNITED STATES PATENT OFFICE.

ALBERT ARTOPOENS, OF PFORZHEIM, GERMANY.

CONSTRUCTION OF JEWELRY.

SPECIFICATION forming part of Letters Patent No. 761,867, dated June 7, 1904.

Application filed December 29, 1903. Serial No. 186,962. (No model.)

To all whom it may concern:

Be it known that I, ALBERT ARTOPOENS, manufacturer, a citizen of the German Empire, residing at Lindenstrasse 36, in the town 5 of Pforzheim, in the Grand Duchy of Baden, Germany, have invented a new and useful Improvement in the Construction of Jewelry, entitled "Bijouterie-Link for Construction of Necklaces, Bracelets, Fretwork, and the Like," 10 of which the following is a specification.

The present invention relates to the construction of linked chains and fretwork in jewelry.

Hitherto for the secure fixing of connected links or parts lying close together in necklaces, bracelets, and the like a most wearisome manipulation has been necessary. Such parts must singly have provision of pins and eyes and slits, one fitting into the other to form 20 needed means of junction. Then separate solderings must be made preliminary to a general soldering of the whole together in any certain desired design. Thus production is replete with difficulties, more especially with 25 regard to the collets or sockets for the setting of precious stones in the aforementioned articles of jewelry.

With the improved link constituting this invention after connection of the separate 30 empty or open links a collet can be soldered on. Such soldering on of the same is here greatly facilitated by having said collets topped or sheathed previously with solder. Thus they are simply placed one alongside another on the connected links and may all at 35 one time be soldered on in quantities.

In the eight figures of the accompanying sheet of drawings this new bijouterie-link is shown separately and also as forming parts 40 in the construction of articles of jewelry composed of chains and fretwork.

Figures 1 to 5 display this new link in different stages of its formation and from various aspects, with resulting shapes and means 45 of connection. Fig. 6 gives an illustration of links of this description when connected together so as to form a chain; Fig. 7, a horizontal section through a row of such links having collets soldered on; Fig. 8, an example 50 of these links when used and connected in

the construction of fretwork, network, and the like in articles of jewelry.

The first operation in the production of this new bijouterie-link is the punching out, by means of special tools, from sheet metal of 55 an oblong preparatory plate having at each side small rectangular wings or shoulders of greater or lesser width. The wider of such shoulders are perforated by this same operation, receiving a circular aperture thereafter 60 to be used as an eye a^4 . The narrower unperforated shoulders are utilized to serve as pins or hooks a^3 . In related articles of jewelry needing broader construction there may be such greater number provided and 65 such varied arrangement of the foregoing hooks a^3 and eyes a^4 on each link as will best promote the manufacture of the intended article. For example, one link may have four eyes a^4 and its complementary link four hooks 70 or pins a^3 , or, as with examples given in Fig. 8, each link may have two eyes and two hooks; but whatever number of eyes and hooks or pins may be required they are all stamped out with the preparatory plate by 75 this first operation. The simplest form of the preparatory plate, having one eye and one hook only, is exhibited in Fig. 1. Then such preparatory plate is operated upon in a circular mold or die prepared for the purpose 80 by means of a suitably-shaped stamp. Thereby the pan or capsule a is pressed or plunged out of the central portion of said plate, the sides a^1 and a^2 and the hook part a^3 are simply raised, and the eye part a^4 is brought up 85 so as to lay out horizontally about one thickness of the sheet metal higher or above the floor of the pan. This accomplished, the bijouterie-link is then ready for use. The collets b , Fig. 7, are constructed in a precisely 90 analogous manner. Their outer edges are set firmly in knees at the outer width of the capsule a and there soldered fast.

The coupling or attachment together as elements in articles of jewelry of these bijouterie-links by their eyes and hooks is effected 95 as more particularly displayed in Fig. 6.

What I claim as my invention, and desire to secure by Letters Patent, is—

A bijouterie-link stamped in one piece out 100

of sheet metal, which link has integral hinge members a^3 a^4 for uniting link with link as forming elements in certain articles of jewelry, and which link has also collets b soldered thereto as settings for precious stones, all substantially as set forth.

5 In testimony whereof I have signed my name

to this specification in the presence of two subscribing witnesses.

ALBERT ARTOPOENS.
